DESIGN FOR A CLOCK CASE

John P. Rainbault, New York, N. Y., assignor to
General Electric Company, a corporation of
New York

Application September 14, 1933. Serial No. 49,256

Term of patent 14 years

To all whom it may concern:

Be it known that I, JOHN P. RAINBAULT, a citizen of the United States, residing at New York, county of New York, State of New York, have invented a new, original, and ornamental Design for a Clock Case, of which the following is a specification, reference being had to the accompanying drawing forming a part thereof. Fig. 1 is a front perspective view of a clock case showing

my new design; and Fig. 2 is a side elevation of the same.

I claim:

The ornamental design for a clock case as shown.

In witness whereof, I have hereunto set my hand this sixth day of Sept., 1933.

JOHN P. RAINBAULT.
